Primary Examiner — Marie D. Fast Horse(74) *Attorney, Agent, or Firm* — Wolf, Greenfield & Sacks, P.C.(57) **CLAIM**

The ornamental design for a base station housing, as shown and described.

DESCRIPTION

FIG. 1 is an upper front right perspective view of a base station housing showing our new design;

FIG. 2 is an lower front right perspective view thereof;

FIG. 3 is a front view thereof;

FIG. 4 is a right side view thereof;

FIG. 5 is a left side view thereof;

FIG. 6 is a rear view thereof;

FIG. 7 is a top view thereof; and,

FIG. 8 is a bottom view thereof.

The broken lines consisting of unevenly sized dashes define the boundary of the claim, which extends to the boundary but does not include the boundary, while all other broken lines depict portions of the base station housing that form no part of the claimed design.
